UNITED STATES PATENT OFFICE

MAURICE CHARLIER, OF BRUSSELS, BELGIUM

PROCESS OF SWAGING DENTAL PLATES

Application filed June 21, 1928, Serial No. 287,219, and in Belgium June 25, 1927.

The present invention relates to a new and improved method of swaging metal plates for dental apparatus, and more particularly the kind of plates made of metal of high 5 mechanical resistance such as rustless steel.

The object of this invention is to make it possible and practical to manufacture such high resistance metal plates in the dentist's laboratory itself, without having to call upon 10 specialized workshops or factories.

The metal plate to be swaged on a metal die is fixed in position by means of a lever with adjustable pressure; between the operating end of the lever and the plate is interposed a mass of soft metal, such as lead or tin, which is subjected to hammering from the centre of the die outwards; this soft metal may be in the form of a strip which is wound 15 into a spiral as the hammering proceeds from the centre outwards, said strip being held by said lever with the interposition of a small 20 plate of suitable size.

Instead of a strip the soft metal may be shaped as a plate of the size to be swaged and 25 of suitable thickness.

The device for supporting and clamping the die, the plate to be swaged and the accessory parts comprises a base on which is arranged a standard serving as a pivot for a 30 lever which presses on the die towards the centre thereof; any suitable clamping means may be adapted to said swinging lever.

In order that my invention may be better understood I have illustrated by way of example 35 in the accompanying drawings, an apparatus for carrying out the process according to the invention. In the drawing:

Fig. 1 is a vertical section of a die for swaging, on which is laid the plate to be hammered.

Figs. 2 and 3 are plan views corresponding to Fig. 1, diagrammatically showing the winding of the soft metal strip in two successive phases.

Fig. 4 is an elevation of the apparatus complete.

Fig. 5 is a plan view of the clamping lever.

Referring to said drawing, 1 denotes the base of the apparatus; a standard 2 screwed 50 in said base forms a horizontal pivot 5 for

the swinging lever 3 which is serrated or milled at its flattened end 4.

This lever is provided with an oblong slot 6 through which extends a threaded rod 7 hooked at its lower end 9 to an eye 10 screwed 55 into the base 1, while its end above the lever 3 carries a clamping nut 8.

11 is the metal die on which is to be swaged the high resistance metal plate 14, which is for example of rustless steel; this die is secured 60 in position on the base 1 by lugs integral with the latter, or by any other suitable means. The swaging operation is effected in the following manner: The dental plate 14 is first subjected to a brief hammering in order 65 to shape it to the shape of the palate; it then is placed on the die in the position where the whole must be pressed.

At that moment there is introduced between the dental plate 14 and the end 4 of the 70 lever 3 a strip 12 of soft metal, for example lead or tin, the first coil of which, of spiral shape, is clamped by the nut 8 of the lever 3, which firmly secures the whole in position and presses on the centre of the plate. Successive 75 coils of the soft metal strip are then pressed and hammered, as they are gradually wound, the effect of which is to press and spread the dental plate 14 without folding or tearing the metal.

A set of intermediate plates of various thicknesses permits of maintaining and pressing each portion of the soft metal strip or plate while hammering is gradually proceeded with, these plates being placed under 85 the finger of the lever. The strips or plates of soft metal may be cast to various sizes by means of moulds so that the same soft metal can be used indefinitely.

From the foregoing it will be understood 90 that the dental plate 14 thus obtained will exactly follow the contour of the die owing to the hammering with interposition of a soft metal, and that on the other hand, owing to the gradual hammering from the centre 95 towards the periphery of the die, the metal of the dental plate although having a great mechanical resistance, will neither fold nor tear at any place.

The cost of manufacturing such a dental 100

plate will be much less than that of the present plates of gold or other precious metal, on the one hand because its weight will be much less, and on the other because its cost, 5 by equal weight, is lower.

I claim:

In a process of swaging thin plates of high mechanical resistance, placing the plate on a die, placing a strip of soft metal on the plate, 10 one end of said strip being approximately at the centre of said plate, fixing said end on the plate by mechanical pressure, gradually winding said strip in a spiral around its fixed end and hammering said strip while it is 15 being wound from the centre outwards.

In testimony whereof I affix my signature.
MAURICE CHARLIER.
